UNITED STATES PATENT OFFICE.

HERMAN FREDERICK SIMON, OF FITCHBURG, MASSACHUSETTS, ASSIGNEE TO PARKS-CRAMER COMPANY, OF BOSTON, MASSACHUSETTS, A CORPORATION OF MASSACHUSETTS.

VAPORIZING APPARATUS.

Application filed September 16, 1921. Serial No. 501,215.

To all whom it may concern:

Be it known that I, HERMAN FREDERICK SIMON, a citizen of the United States, and resident of Fitchburg, county of Worcester, 5 State of Massachusetts, have invented an Improvement in Vaporizing Apparatus, of which the following description, in connection with the accompanying drawing, is a specification, like characters on the drawing 10 representing like parts.

This invention relates to improvements in vaporizing apparatus and particularly to that type of vaporizing apparatus which is employed in the humidification of enclosures, and the general object thereof is to provide a more economically constructed and more easily regulated apparatus than has been heretofore produced.

More specifically the present invention relates to improvements in humidifying apparatus of the "Turbo" head type which is disclosed in the following patents:—No. 869,945 A. W. Thompson, November 5, 1907; No. 968,074 Parks, August 23, 1910; and, 25 No. 1,227,190 Parks, May 22, 1917.

In vaporizing apparatus of this general type the amount of moisture delivered to the atmosphere of the enclosure is controlled in one of two ways, either by automatically 30 shutting off all of the atomizers when the room has reached the predetermined degree of humidity and turning them on again automatically when the humidity decreases below said predetermined degree, or by 35 regulation of the individual atomizer heads which deliver water vapor to the air of the room. In the latter case the regulation usually is done manually, a valve being provided for controlling the air under pressure 40 which is supplied to each of the humidifier heads. This requires a separate valve for each head. The present invention contemplates the provision of a unit having a plurality, preferably two, atomizer heads and provided with a single regulating valve which may be operated to selectively cause one or more of the atomizer heads to operate, or which may be so actuated as to prevent the operation of any of the atomizer 45 heads connected with it.

A further object of the invention is to provide a vaporizer of this character with a plurality of atomizer heads which may be adjusted at different angular relations in order that the vapor produced by the head 55 may be projected in different desired directions within the room.

A further object of the invention is to provide means for supplying each of the atomizer heads with the liquid to be vaporized without the possibility of interruption of the action of said atomizer head caused by back pressure produced by the shutting off of another atomizer head. This is accomplished by providing a separate liquid 60 delivery pipe for each of the atomizer heads and causing said pipe to communicate with the liquid supply below the normal level at which the liquid is maintained in the system 65 which supplies the liquid to the atomizers.

Other objects and features of the invention will more fully appear from the following description and the annexed drawings and will be pointed out in the claims. 75

In the drawings:

Fig. 1 is a front elevation of a vaporizing apparatus embodying my invention, certain of the conduits for supplying liquid to the atomizers being shown in vertical section; 80

Fig. 2 is a plan view of the same;

Fig. 3 is a vertical longitudinal sectional view through the valve casing through which air under pressure is supplied to the atomizer heads, the valve being shown 85 mainly in elevation; and,

Fig. 4 is a horizontal sectional view through the valve casing on line 4—4, Fig. 3, viewed from the left.

The vaporizing apparatus illustrated in 90 the accompanying drawings comprises a conduit 1 through which the gaseous fluid under pressure, such as compressed air, is supplied from a suitable source and a main liquid supply conduit 2 through which the water, or other liquid to be vaporized, is supplied, preferably from a usual tank. The conduits 1 and 2 may be supported in any desirable manner upon posts, or from 95 the ceiling of the room, and the main liquid 100

supply conduit desirably is located below the conduit which supplies the gaseous fluid. In any event the conduits are so arranged that the atomizer heads shall be above the liquid level which is maintained in the tank. This construction, however, is old and is so well known to those skilled in the art that further description thereof is deemed unnecessary.

10 In the preferred embodiment of the invention disclosed herein a vaporizer unit having two atomizer heads is mounted upon the conduit which supplies gaseous fluid under pressure. As illustrated a pipe 3 is threaded through one section 4 of a clamp and registers with or extends into an aperture in a soft metal bushing 5 which embraces a tapped segment of the conduit 1. The complementary section 6 of the clamp 15 embraces a diametrically opposite segment of the conduit 1 and the sections 4 and 6 are clamped together by bolts 7. A union of this character can be conveniently made at any point along the conduit either before 20 or after its installation.

The upper end of the pipe 3 is provided with a flange 8 which forms a seat for the enlarged screw threaded portion 9 of a stem 10 of the vaporizer unit, a suitable 30 gasket 11 being placed between the flange 8 and the enlarged portion 9 of said stem. A nut 12 having a flange underlying the flange 8 and a screw threaded portion engaging the threads of the enlarged portion 9 of the stem provides a coupling which can be readily and quickly assembled.

The stem 10 desirably is formed integral with the body 13 of the vaporizer unit, said body being provided with integral and oppositely extending members 14 and 15 forming a casing for a plug valve 16. Laterally extending bosses 17 and 18 form arms of a T leading to the atomizer heads.

In the present construction short pipes 19 and 20 are screw threaded at their inner ends into the bosses 17 and 18 and are connected at their outer ends to the vaporizers by couplings 21 and 22 similar to that which connects the pipe 3 to the stem 10 of the vaporizer unit. The atomizer heads 23 and 24 desirably are of the "Turbo" type in which the gaseous fluid under pressure is introduced tangentially into a chamber within the head, the liquid being fed or supplied through a small conduit extending axially of the head so that a whirling jet of air is caused to surround and impinge upon the jet of liquid issuing through the conduit in the head. Other suitable types of atomizers, however, may be employed within the spirit and scope of my invention.

As before stated it has heretofore been customary to provide each of the atomizer heads with a regulating valve. The present invention contemplates the regulation of

either or both of said heads by a single valve. In the preferred embodiment of the invention illustrated herein the valve 16 is in the form of a tapered plug valve which is seated in a correspondingly tapered 50 aperture in the body portion 13 of the vaporizer unit. This valve is provided with three radially extending ports 25, 26 and 27, two of said ports 25 and 26 being in axial alignment and the other port 27 normal to and communicating with both the ports 25 and 26. By reason of this construction the valve 16 may be so positioned, (as illustrated in Fig. 4), as to establish communication from the conduit through the stem 10 with both atomizers, or by a ninety degree rotation from this position in one direction may be caused to communicate with one atomizer and cut off the other, or by a rotation of ninety degrees in the opposite direction 55 may be caused to cut off the first and communicate with the second mentioned atomizer. By rotating the valve through one hundred eighty degrees the solid portion 28 of the valve will cover the aperture through 60 the stem 10 thereby cutting off the supply of fluid under pressure to both the atomizers.

The plug valve 16 may be retained in its seat in any suitable manner. As illustrated herein the upper end portion of the valve 65 16 is provided with a shoulder which is engaged by a washer 29 which fits the valve aperture in the body portion of the unit and is firmly held in its seat by a bushing 30 which is engaged by a cap 31 having screw 100 threaded engagement with the outer wall of the laterally extending member 14 of said unit. The valve 16 is provided with a stem 32 having an angular end portion 33 to receive a handle or a wrench 34. The liquid, 105 which in humidifying systems is water, is supplied to the atomizer heads 23 and 24 respectively through preferably flexible pipes 35 and 36 of copper or other pliable material which communicate with the liquid 110 supply conduit 2.

In this type of apparatus the liquid is drawn from a riser through the pipes leading to the vaporizer by the action of inspiration of the gaseous fluid under pressure 115 rushing through the atomizer head around the nozzle with which the pipe 35 or 36 communicates. It has been found by experience that where the pipes leading to a plurality of atomizer heads communicate with the upper end of the riser the shutting off of one head may cause a momentary back pressure of the air or other gaseous fluid under pressure in the pipe leading to the atomizer, thus closed, which will drive down the liquid in 120 the riser so that the other atomizer head will be rendered ineffective. The present invention includes means for preventing this contingency. As illustrated herein the pipes 35 and 36 are connected respectively to the 125 130

branches 37 and 38 of a T of special formation, the stem 39 of which is screwed upon the upper end of a riser pipe 40 which is connected to the liquid supply conduit 2 by a suitable coupling comprising clamping members 41 and 42 and a bushing 43 similar to the connection which unites the pipe 3 with the gaseous fluid supply conduit 1.

In the present construction the arm 38 of the T is provided with an axial bore 44 which communicates with a duct 45 which leads directly to the riser 40. The arm 37 of the T is provided with an axial bore 46 which extends to or beyond the center of the T and communicates with a passage 47 which preferably is located axially of the riser 40. A tube 48 which is screw threaded at its upper end into the body of the T extends downwardly, preferably concentrically with the riser 40, to a distance below the normal liquid level in the riser. By reason of this construction each of the atomizer heads is provided with an independent communication extending below the normal level of the liquid in the riser so that the back pressure produced by the trapping of air in either of the pipes 35 or 36, when the atomizer to which it leads is shut off, will not result in disabling the other atomizer.

It will be readily understood that by reason of this construction two atomizer heads may be provided for each vaporizing unit, thus increasing the capacity of the apparatus without materially increasing the cost of installation. Furthermore, each of the atomizer heads may be regulated independently of the other, or both may be actuated or cut off by the operation of a single valve.

By reason of the rotatable connection between the atomizers and the head of the vaporizer unit, and the flexible connection between the atomizers and the water supplying means, the atomizers may be adjusted at any desirable angular inclination to the horizontal, and preferably may be so disposed as to project a water vapor in generally opposite directions so that a wider distribution throughout the air of the room will take place than in apparatus heretofore employed.

It will be understood that the present embodiment of the invention is illustrative and not restrictive and that other types of atomizers may be employed and that various changes in construction and arrangement of parts may be made within the spirit and scope of the following claims.

Having thus described my invention, what I claim as new, and desire to secure by Letters Patent, is:

1. A vaporizing apparatus comprising a delivery conduit, for a gaseous fluid under pressure, having a T, an atomizer head ad-

justably secured to each of the oppositely extending branches of said T, a valve in said T having ports arranged to selectively supply said fluid under pressure to one or to both of said branches or to cut off the supply of fluid under pressure to either or both of said branches, water supplying means and flexible conduits connecting said water supplying means with said atomizer heads.

2. A vaporizing apparatus comprising a delivery conduit, for a gaseous fluid under pressure, having a plurality of branches, an atomizer head connected to each branch, means operable to selectively supply fluid under pressure to one or to a plurality of said branches, a liquid supplying pipe having a liquid level lower than the atomizer heads, a duct leading from said pipe to one of said atomizer heads, and an independent conduit leading from said pipe to the other atomizer head communicating with said water supplying pipe below said liquid level therein.

3. A vaporizing apparatus comprising a delivery conduit, for a gaseous fluid under pressure, having a T, an atomizer head connected to each of the oppositely extending branches of said T, a valve in said T having ports arranged to selectively supply fluid under pressure to either of said atomizer heads, a main liquid supplying conduit having a liquid level lower than the atomizer heads, a riser communicating with said main supplying conduit, a T on said riser, a pipe connecting one of the branches of said T with an atomizer head, a conduit leading to the other atomizer head having a member enclosed within said riser and extending below said liquid level.

4. A vaporizing apparatus comprising a delivery conduit, for a gaseous fluid under pressure, having a T, an atomizer head connected to each of the oppositely extending branches of said T, a valve in said T having ports arranged to selectively supply fluid under pressure to either of said atomizer heads, a main liquid supplying conduit having a liquid level lower than the atomizer heads, a riser communicating with said main supplying conduit, a T on said riser, pipes connecting the branches of said T respectively with said atomizer heads, a port in said T leading to one of said branches, and a tube within said riser extending below said liquid level communicating with the other branch of said T.

5. A vaporizing apparatus comprising a delivery conduit, for a gaseous fluid under pressure, having a T, an atomizer head connected to each of the oppositely extending branches of said T, a valve in said T having ports arranged to selectively supply fluid under pressure to either of said atomizer heads, a main liquid supplying con-

duit having a liquid level lower than the atomizer heads, a riser communicating with said main supplying conduit, a T on said riser, flexible pipes connecting the branches of said T respectively with said atomizer heads, a port in said T leading to one of said branches and a tube within said riser

detachably secured to said T, communicating with the other branch and extending below said liquid level.

10

In testimony whereof, I have signed my name to this specification.

HERMAN FREDERICK SIMON.
